(57) **CLAIM**

The ornamental design for a toy construction element, as shown and described.

DESCRIPTION

FIG. 1 is a top perspective view of a toy construction element;

FIG. 2 is a bottom perspective view of the embodiment of FIG. 1;

FIG. 3 is a side elevational view of the embodiment of FIG. 1, the side elevational view 180° from FIG. 3 being identical to FIG. 3, the two side elevational views 90° from FIG. 3 being an inversion of the embodiment of FIG. 3 and identical to one another; and,

FIG. 4 is a top plan view of FIG. 1, the bottom plan view being identical to FIG. 4.
